10 Claims

ABSTRACT OF THE DISCLOSURE

The present invention discloses a one-piece display including a front wall panel, and two side wall panels foldably connected to opposite sides of said front panel and foldable into parallel relation. A supporting strap is hinged to the center portion of the front panel and is foldable to lie inwardly of the front panel. A bottom panel is hinged to the lower edge of the supporting strap, and a display panel is hinged to the rear edge of the bottom panel. The side panels and display panel are provided with interconnecting means to hold the parts assembled.

This invention relates to an improvement in paperboard displays and deals particularly with a one piece structure which may be folded to form a tray-like body having a display panel along the rear thereof.

Display units for containing one or more items of merchandise, pamphlets or other such material have been made in considerable volume. Most of such objects are in the form of trays having a top panel which may be folded into upright position for display purposes. The present device is not designed to contain material during shipment but is designed to provide a display which is normally a flat sheet and which may be quickly and easily folded into a display container having a display panel which is somewhat wider than the pocket into which the items are displayed, and side panels which are somewhat wider than the material being displayed, thus, providing an unusually large display area.

An object of the present invention resides in the provision of a display which includes a front display panel having a pair of side walls hingedly connected to opposite side edges thereof, the side walls being foldable into parallel relation extending rearwardly from the front panel. A supporting strap is hingedly connected to the upper edge of the front panel, and is folded inwardly and downwardly to lie in face contact with the rear surface of the front panel. A bottom panel is hinged to the lower edge of the strap, and a rear wall or display panel is hingedly connected to the rear edge of the bottom panel. The side panels and the display panel are provided with intersecting slots which hold the display in its assembled position.

A feature of the present invention resides in the provision of a display having a display panel which normally slopes rearwardly. The display also includes a bottom wall which is horizontal, or a bottom wall which is at right angular relation to the rear wall and display panel. If individual cartons are to be displayed, the bottom wall may be supported at right angular relation to the rear display panel to hold the articles contained against the rear panel.

These and other objects and novel features of the present invention will be more clearly and fully set forth in the following specification and claims.

In the drawings forming a part of the specification:

FIGURE 1 is a perspective view of the display in set up position.

FIGURE 2 is a vertical sectional view through the

2

display, the position of the section being indicated by the lines 2—2 of FIGURE 1.

FIGURE 3 is a vertical sectional view through the display at right angles to FIGURE 2, the position of the section being indicated by the line 3—3 of FIGURE 2.

FIGURE 4 is a diagrammatic view showing the blank from which the display is made.

FIGURE 5 is a view similar to FIGURE 2 showing the walls proportioned so that the bottom panel is at right angles to the rear or display panel.

As is indicated in FIGURE 4 of the drawings, the display A includes a front wall panel 10 which is hingedly connected by fold lines 11 at opposite end edges to side panels or wings 12. As indicated in FIGURE 4, the lower edges 13 of the side walls 12 are in equal angular relation to the lower edge 14 of the front panel 10, the degree of angle between the edges 13 and 14 determining the extent to which the front wall 10 will slope rearwardly.

As indicated in the drawings, a pair of cut lines 15 define the upper edges of the side portions of the front wall 10, the cut lines 15 sloping downwardly and inwardly from the upper corners 16 of the front wall. The inner opposed ends 17 of the cut lines 15 curve downwardly toward parallel relation, and these cut line ends 17 are connected by a double score line 19 extending parallel to the lower edge 14 of the front panel 10. This arrangement provides a substantially trapezoidal strap 20, the shorter parallel edge of which is defined by the fold lines 19, and the wider parallel edge 21 is defined by a fold line connecting the supporting strap 20 to the rectangular bottom panel 22. The bottom panel 22 is of proper width to fit between the side walls 12 when these side walls are folded into right angular relation to the front panel 10.

The bottom panel 22 is hingedly connected by a fold line 23 to a rear wall or display panel 24, the fold line 23 being parallel to the fold line 21. In the particular arrangement illustrated, the side walls 12 increase in height from their bottom edges 13 to their rear edges 25. Slots 26 are provided in the upper edges of the side walls 12, or generally at the intersection between the upper edges 27 of the side walls 12 and the end edges 25 thereof. The slots 26 extend parallel to the fold lines 11 connecting the front wall 10 to the side walls 12. While this is a matter of choice, having the slots 26 parallel the fold lines 11 results in having the rear wall 24 parallel to the front wall 10.

The display panel 24 is provided with laterally extending projections 29 which terminate in spaced relation to the fold line 23, and slots 30 are provided extending into the projections 29, the slots 30 forming continuation of the side walls 31 of the lower portions of the rear wall. The distance between the base of each slot 30 and the fold line 23 is substantially equal to the distance between the base of each notch 26 and the lower edge 13 of the side walls. Thus, when the slots 26 and 30 are interlocked together, as indicated in FIGURES 1 and 2 of the drawings, the bottom panel 22 is substantially horizontal as indicated in FIGURE 2.

In the event, the display A is designed to contain small cartons or other objects which are designed to be supported against the rear wall, the height of the front panel may be increased and the length of the strap decreased as indicated in FIGURE 5 of the drawings. As indicated in this figure, the front panel 110 is formed so that the transverse fold lines 119 are somewhat higher than in FIGURE 2 of the drawings, and the strap 120 is correspondingly shorter. The bottom wall 122 may accordingly be supported in right angular relation to the rear panel 124 by the side walls 112 when the side walls and rear panel are interlocked.

In accordance with the patent statutes, I have described

the principles of construction and operation of my display; and while I have endeavored to set forth the best embodiment thereof, I desire to have it understood that obvious changes may be made within the following claims without departing from the spirit of my invention.

I claim:

1. A display including:

a front panel,

side wall panels hinged to opposite ends of said front panel,

10 a supporting member secured to the upper edge of said front panel and foldable inwardly of said front panel, a bottom panel hinged to the lower end of said supporting member,

15 a rear display panel hinged to said bottom panel, and cooperable means on said display panel and on said side wall panels to hold said display panel in fixed relation between said side panels.

2. The structure of claim 1 and in which said display panel and said side wall panels include interlocking slots 20 which form said cooperable means.

3. The structure of claim 1 and in which said cooperable means holds said display panel substantially parallel to said front panel.

4. The structure of claim 1 and in which said supporting member is hinged to the center portion of said front panel by fold lines terminating in spaced relation to the sides of said front panel, and said front panel slopes upwardly to the sides of said front panel.

5. The structure of claim 4 and in which said supporting member is substantially the full width of said front panel at its lower edge.

6. The structure of claim 4 and in which said side wall panels increase in height toward their connection with said display panel.

7. The structure of claim 4 and in which said connecting member is substantially trapezoidal in shape with a short parallel edge hinged to said front panel and a wider parallel edge hinged to said bottom panel.

8. The structure of claim 1 and in which the lower 40 edges of said side walls are equally angularly related to

the lower edge of said front panel to hold said front panel upwardly and rearwardly inclined.

9. A display including:

a front wall panel,

a pair of side wall panels foldably connected to opposite sides of said front panel,

the lower edges of said side walls being equally angularly related to the lower edge of said front panel to hold said front panel upwardly and rearwardly inclined when said side wall panels are folded rearwardly from said front panel,

a supporting strap hingedly connected to said front panel along a line of fold which terminates short of the sides of said front panel,

said supporting strap being folded downwardly rearwardly of said front panel and being substantially equal in width to said front panel at its lower edge, a bottom panel hinged to the lower edge of said strap and extending rearwardly therefrom,

a rear display panel hingedly connected to the rear edge of said bottom panel,

said side walls having slots extending downwardly from the upper edge thereof,

said display panel having downwardly facing slots interengageable with the slots in said side walls.

10. The structure of claim 9 and in which said slots in said side panels are substantially parallel to said front wall.
